UNITED STATES PATENT OFFICE.

FRANK J. DUFFNER, OF ALLEGHENY, PENNSYLVANIA.

DESIGN FOR A LAMP-DOME.

SPECIFICATION forming part of Design No. 31,237, dated July 18, 1899.

Application filed June 18, 1898. Serial No. 683,861. Term of patent 7 years.

To all whom it may concern:

Be it known that I, FRANK J. DUFFNER, a resident of Allegheny, in the county of Allegheny and State of Pennsylvania, have invented a new and original Design for Lamp-Domes; and I do hereby declare the following to be a full, clear, and exact description thereof.

My design relates to lamp and like domes; and the leading or material feature thereof consists in a base portion which curves or rounds under the body and thence upwardly within the body, so that the lower edge of the dome is concealed from view.

In the accompanying drawings, illustrating my design, Figure 1 is a side view of the dome, and Fig. 2 is a vertical section.

As shown in the drawings, the dome has the body *a*, which flares downwardly toward the base *b*. The base *b* is formed curved or rounded under the body, as at *c*, and thence upwardly within the body of the dome, as at

d, so that the lower edge *e* of the dome is above the base thereof and is concealed thereby. Within the dome the edge turns downwardly to form a lip *f* and seat *g* to support the dome on the lamp, such lip and seat being above the base of the dome.

The dome has a handsome appearance, its base portion rounding under the body on graceful lines, which vanish in substantially the same course, while the lower edge of the dome is entirely concealed.

What I claim is—

The design for a lamp-dome herein shown and described.

In testimony whereof I, the said FRANK J. DUFFNER, have hereunto set my hand.

FRANK J. DUFFNER.
